TABLE OR THE LIKE

Herbert Ritts, P.O. Box 64336, Los Angeles, Calif.

Filed Jan. 21, 1963, Ser. No. 73,245

Term of patent 7 years

(Cl. D33—14)

I claim:

The ornamental design for a table or the like, substantially as shown and described.
